UNITED STATES PATENT OFFICE

PHILIP A. JACKSON, OF DAYTON, OHIO

AUTOGRAPHIC REGISTER

Application filed August 23, 1930. Serial No. 477,313.

This invention relates to autographic registers and one object of the invention is to provide such a register having simple easily operated means for advancing the webs upon which the record is to be made and for retaining said webs in their proper relative positions.

A further object of the invention is to provide such a register in which the supply of paper, or forms on which the records are to be made, and the writing table will move together to advance the forms successively to writing position.

A further object of the invention is to provide such a register in which the writing table forms part of a web feeding device for moving successive portions of the webs into a position to receive the record and having means for holding that portion of the web on which the record has been written against movement while the writing table is moved into a position beneath another portion of the web and for then releasing the first mentioned portion of the web to permit it to be ejected from the register when the second portion is moved into writing position.

A further object of the invention is to provide such a register in which the web holding devices will be automatically controlled by the movement of the writing table.

A further object of the invention is to provide such a register in which the web feeding mechanism will be of such a character that it will not project beyond the front end of the register at any time, thereby permitting the several forms to be folded one upon the other in front of the register.

A further object of the invention is to provide an autographic register of such a character that it will issue forms or bills of different lengths without change in the mechanism.

Other objects of the invention will appear as the mechanism is described in detail.

In the accompanying drawings Fig. 1 is a plan view of a register embodying my invention, partly broken away; Fig. 2 is a side elevation of such a register, partly in section to show the operating mechanism;

Fig. 3 is a section through the upper part of the register, taken on the line 3-3 of Fig. 1; Fig. 4 is a transverse section taken on the line 4-4 of Fig. 2; Fig. 5 is a transverse section taken on the line 5-5 of Fig. 2; Fig. 6 is a sectional view showing the operating mechanism in elevation; Fig. 7 is a detail of one of the forms showing the arrangement of the openings therein; Fig. 8 is a longitudinal sectional view showing the modified form of operating mechanism; Fig. 9 is a sectional detail showing the relative size of the openings in the webs and one of the holding pins; and Fig. 10 is a detail view from the connection between the stop pawl and one of the holding pins.

In these drawings I have illustrated one embodiment of my invention, together with a minor modification thereof, but it will be understood that this particular embodiment has been chosen for the purpose of illustration only and that the mechanism may take various forms without departing from the spirit of the invention.

In the particular embodiment here illustrated the register comprises a supporting frame which, in the present instance, is shown in the form of a casing rectangular in cross section, and having its top wall 11 hinged at its forward end, as shown at 12, to permit it to be raised to provide access to the interior of the casing. This top wall has in its forward portion an opening 13 beneath which the writing table is located when it is in its operative position. Mounted on the supporting frame is a carriage which is adapted to support a plurality of superimposed webs of paper or the like on which the records are to be written and this carriage has a part forming a writing table which is so arranged that the superimposed webs may be led about the rear end of the table and positioned on the upper surface thereof. In the present register the carriage is in the form of a casing 14, which constitutes a container for the webs which are usually provided with printed forms and which, in the present instance, are folded in sections each of which is equal in length to the length of one of the forms, the forms being thus stacked one upon the other,

as shown at 15. The top wall 16 of the container constitutes the writing table and is located just below the top wall 11 of the outer casing or supporting frame. Arranged between the top walls 16 and 11 is a hinged cover 16a which has an opening above the writing table. The container is movably mounted within the outer casing for movement lengthwise thereof and, in the present instance, the container has at its lower lateral edges flanges 17, which are slidably mounted in channeled tracks or guides 18 in the lower portion of the outer casing. The superimposed webs are led upwardly, as shown at 19, through an opening in the top of the casing and in the rear of the writing table and preferably about a guide roller 20 and then carried forward above the writing table, the forward edges projecting slightly beyond the writing table. When the carriage is moved to its foremost position the projecting ends of the webs will enter a guideway or slot 21 at the forward end of the outer casing and means are provided for engaging these ends of the web and holding the webs against movement while the carriage is moved to its rearmost position to position the writing table beneath a second section or form of the web, it being obvious that as the writing table is moved rearwardly the forms will be withdrawn from the stack 15 in the container.

The means for holding the webs against rearward movement with the carriage may take various forms but the present register was designed for use with forms having near their forward ends openings 22, these openings being spaced equal distances apart lengthwise of the webs and corresponding openings in the several webs being arranged in vertical alinement so that each set of openings through the several webs will constitute in effect a single opening. I have therefore provided the holding device in the form of pins 23, one for each opening in the webs, and have mounted these pins above the slot or guideway 21 in the outer casing so that they can be moved through the top wall of that slot and into the openings in the webs when the latter are properly positioned in the slot. The pins are carried by a supporting member 24 which is pivotally mounted at 25 on the outer casing and provided with a rearwardly extending arm 26. The movement of the holding device into and out of the openings in the webs is controlled by the movement of the carriage and the actuating means therefor are of such a character that while the carriage is near its foremost position, the pins will be moved into the openings in the web. This, of course, must be accomplished while the carriage is in motion and the movement may be effected either just before the carriage completes its forward movement or just as it begins its rearward movement. In the form here shown the pins are moved into operative

engagement with the webs just as the carriage completes its forward movement.

A suitable actuating device is operatively connected with the web holding device and this actuating device and the carriage have parts which cooperate to cause the pins of the holding device to be moved into and out of the webs at the desired times as determined by the position of the carriage. In the present construction the actuating device comprises a bar 27 extending lengthwise of the outer casing and along one side of the carriage and this bar is mounted for a limited longitudinal movement and a limited vertical movement. These movements may be secured in any suitable manner, as by providing the bar with inclined slots 28 to receive pins 29 mounted in the side wall of the outer casing. The slots are so arranged that when the bar is moved forwardly it will also be moved upwardly and when moved rearwardly it will also move downwardly. This bar is connected with the arm 26 of the web holding device by means of a link 30 so that the movement thereof is transmitted through the supporting member 24 to the pins. It will be apparent that the rearward and downward movement of the actuating bar will lift the pins and that the forward and upward movement of the bar will depress the pins. The cooperating parts of the carriage and the actuating device may take various forms but as here shown, the actuating bar is provided with stops and the carriage has parts arranged to engage those stops and thus impart movement to the bar. In that form of the device shown in Figs. 1 to 6 the bar has at its forward end an inwardly extending lug 31 arranged in the path of a lug 32 secured to the adjacent side of the carriage and so positioned that when the actuating bar is in its rearmost position the lug 32 will engage the lug 31 as the carriage approaches its foremost position and the continued movement of the carriage will thus impart forward and upward movement to the actuating bar. In order that the rearward movement imparted to the carriage may be varied to accommodate the same to forms of different lengths the actuating bar is provided with a series of stops spaced along the same and in the present instance comprising ratchet teeth 33 formed on a second bar 33a which is rigidly secured to the actuating bar and spaced below the upper edge thereof. Pivotally mounted in the carriage is a rearwardly extending pawl 34 which is normally supported with its nose just above the ratchet teeth 33 but is so controlled that as the carriage approaches the rearward limit of its movement, as determined by the length of the form, the pawl will be caused to drop into engagement with one of the ratchet teeth 33 and the further movement of the carriage will impart a

rearward and downward movement to the actuating bar, thus lifting the holding pins 23 out of the openings in the webs and releasing the webs so that when the carriage is moved forwardly the forward portions of the webs, or the forms on which the record has been written, will be pushed through the slot 21 beyond the holding device and the second form, which has been positioned above the writing table, will be advanced to bring the openings therein into line with the pins 23. As the openings move into this position the carriage will cause the pins to be moved downwardly into the openings.

Inasmuch as the webs are supported wholly by the carriage and there is little or no resistance to the forward movement of those portions of the webs which are being ejected it is not essential that there should be any means for causing the webs to move forwardly with the carriage, but to prevent the accidental displacement of the webs and to insure that the same will be accurately located I prefer to provide some means for so connecting the webs with the carriage that they will be positively moved therewith. This means may take various forms. As shown in Figs. 1 to 6 it comprises a second set of pins 35 movably mounted on the carriage beneath the webs and adapted to engage the under surface of the lower web and to move along the same until the pins are brought into line with the openings at the forward end of the second set of forms and to then enter those openings. The pins 35 are here shown as carried by a lever 36 which is rigidly mounted on a shaft 37 extending transversely to the carriage and the rear end of the lever is weighted, as shown at 38, to press the pins against the lower web and to cause them to enter the openings as soon as they are brought into line therewith. This movement of the pins into the openings in the second set of forms controls the movement of the pawl 34, thus causing that pawl to be moved into operative engagement with the stop on the actuating bar. To this end the pawl is so mounted on the shaft 37 that when the pins are in engagement with the under surface of the lower web the pawl will be supported just above the ratchet teeth or stops 33 and when the pins enter the openings in the webs the action of the weight 38 will cause the pawl to drop into engagement with the adjacent tooth 33. When the pawl has moved to its operative position the further rearward movement of the carriage will move the actuating bar rearwardly and thus cause the holding pins 23 at the forward end of the register to be moved to their inoperative positions and when the bar has been moved to the limit of its movement the rearward movement of the carriage will be interrupted. To prevent the movement of the pawl as it rides over the ratchet teeth 33 upon the forward movement of the carriage from being transmitted to the pins 35 the pawl is loosely mounted upon the shaft and is provided with a forwardly extending lug 134 which is arranged beneath a lug 135 rigidly secured to the shaft. (Fig. 10.) The lugs are so arranged that when the pins 35 are in the openings in the webs the pawl will have free movement sufficient to permit it to ride over the teeth but when the pins are forced out of the openings the lug 135 will engage the lug 134 and lift the pawl out of engagement with those teeth. To prevent those portions of the web, or the forms, which extend between the holding pins 23 and the carriage from sagging, after the pins 23 have been moved to their inoperative positions, a plate 39 extends rearwardly from the forward end of the outer casing beneath the writing table and is of such length that it will completely bridge the space between the guideway 21 and the carriage in all positions of the latter. To permit the pins 35 to engage the lower web this plate 39 is provided with longitudinal slots 40. When the carriage is moved to its foremost position the pins 35 which are in engagement with the second set of openings in the webs will be moved directly beneath the pins 23 which are then in their inoperative positions, and when the actuating device is operated to move the pins 23 into this second set of openings the pins 23 press the pins 35 out of the openings and hold them in their inoperative positions until the carriage has been moved rearwardly and the pins 35 caused to engage the lower web. The pins 35 are of a diameter considerably less than the diameter of the openings in which they engage. Consequently after the pins have entered the openings the carriage may have a slight rearward movement before the pins engage the rear edges of the openings. This movement is sufficient to cause the pawl 34 to start the movement of the actuating bar 27 and thereby impart initial movement to the pins 23. These pins 23 are also somewhat smaller than their openings and they are so mounted that as they move upwardly they also move slightly rearwardly, thus permitting a slight rearward movement of the web before the pins 23 are entirely withdrawn, but a very slight movement of the actuating bar is sufficient to entirely withdraw the pins. Therefore, after the pins 35 have engaged the rear edges of the second set of openings in the webs the carriage will continue its movement, carrying the webs rearwardly with it, until the movement of the carriage is positively stopped. This rearward movement of the webs will in no way affect their ejection from the register because they are supported on the plate 39 which forms the lower wall of the slot 21 through which they are ejected.

Means are also provided to make it necessary

sary for the operator to complete the movement of the carriage in the direction in which it has been started before that movement can be reversed. The ratchet teeth 33 on the side of the actuating bar are extended forward such a distance that the pawl 34 will remain in engagement therewith until the carriage has completed its forward movement and the pins 35 depressed. Hence this pawl and ratchet bar serve to prevent the rearward movement of the carriage until it has first completed its forward movement. The rack bar 27 is provided in its upper edge with a series of rearwardly facing ratchet teeth 41 and a pawl 42 is mounted on the shaft 37 and arranged to engage these ratchet teeth when the actuating bar 27 is in its elevated position, as it is when the carriage is being moved rearwardly. When the carriage reaches the rearward limit of its movement the bar moves downwardly and the teeth are moved out of engagement with the pawl 42, the downward movement of the latter being limited by a stop 43. Thus the pawl 42 will prevent the forward movement of the carriage until it has completed its rearward movement but will then permit that forward movement. The pawl 42 is loosely mounted on the shaft 37 so that the movement imparted thereto as it rides over the ratchet teeth 41 will not press the pins 35 through the webs.

In the operation of the device, after a supply of forms has been placed in the container or carriage, the uppermost forms are led about the guide roller 20 and placed upon the writing table with the openings therein engaged about the pins 35. The carriage is then moved forwardly in any suitable manner, as by means of an operating handle 44, thereby carrying the writing table and the superimposed forms into line with the opening 33 in the top wall of the outer casing and projecting the apertured ends of the forms beneath the ends of the pins 23, which are then caused to enter those openings and disengage the pins 35 therefrom. After the record has been written on the forms the carriage is moved rearwardly, the pawl 34 having been moved to an inoperative position by the depression of the pins 35. This rearward movement of the carriage moves the writing table from beneath the forms upon which the record has been written and beneath a second set of forms which are drawn from the container onto the writing table as the latter moves rearwardly. When the carriage has moved rearwardly far enough to bring the pins 35 into line with the openings in this second set of forms those pins will enter the openings, thereby causing the pawl 34 to engage a stop tooth 33 on the actuating bar and impart movement to that bar which will cause the same to move the pins 23 out of engagement with the first set of forms and

will move the actuating bar to the limit of its movement, thereby stopping the further rearward movement of the carriage. The movement of the actuating bar has lowered the same out of engagement with the detent 70 pawl 42 and the carriage may now be moved forward to bring the second set of forms, now positioned on the writing table, into line with the opening 13 in the top wall of the casing and at the same time moving the first 75 set of forms through the guideway 21 and past the forward holding device and completely ejecting the same. The forward holding pins 23 are then moved into operative engagement with the second set of forms and 80 the pins 35 ejected therefrom in the manner above described. The ejected forms may be disposed of in any suitable manner. Usually all but one of the forms are severed from their webs, as by tearing the same along the 85 cutting edge at the outer end of the guideway, and the forms of the remaining web are permitted to pile up or fold one upon the other at the end of the machine, or in a suitable receptacle. It will be apparent that in this 90 machine this folding operation is possible without the provision of any additional apparatus because the web feeding mechanism does not at any time extend beyond the forward end of the machine.

In Fig. 8 I have shown a slightly different arrangement of the mechanism. As there shown, the supporting structure is in the form of an outer casing 45 and the carriage or container 46 is slidably mounted within 100 the same and the top wall of this container provides the writing table 47 over which the webs are led. The forward web holding device comprises pins 48 mounted on a pivoted supporting device 49 arranged beneath the web supporting plate 50 and guideway 51 so that the pins are moved downwardly to withdraw them from the openings in the webs. The pin supporting member 49 is connected by a link 52 with an actuating 105 bar 53 having inclined slots 54 by means of which it is supported on pins 55 and this bar is provided with ratchet teeth 56 which are engaged by the full stroke pawl 57. The actuating bar is provided with a stop 58 110 adapted to be engaged by a projecting part or lug 59a on the carriage or container 46 so that the rearward movement of the carriage will be imparted to the actuating bar. In order to accommodate the machine to forms 115 of different lengths the actuating bar is provided with a plurality of screw holes 59 spaced lengthwise thereof and each of which is adapted to receive the screw 60 by means of which the stop or lug 58 is secured to the bar, thus enabling the stop to be located in any one of a plurality of positions. The actuating bar is provided near its forward end with a stop 61 adapted to be engaged by the lug 59a on the carriage as the latter ap- 120

- proaches its foremost position. The carriage is not provided with any means for positively connecting the webs therewith during the forward movement of the carriage but a 5 spring 62 mounted above the webs on the carriage exerts sufficient pressure thereon to frictionally hold the webs against displacement and to cause the same to move with the carriage.
- 10 The carriage or inner casing 14 is provided with space at one side of the writing table, as shown at 65, to receive a roll of carbon paper which may be led across the writing table and interleaved between the several 15 webs of paper thereon, so that the carbon paper will move with the carriage and will always occupy its proper position with relation to the writing table. The particular means for supporting the carbon paper and 20 securing it in position form no part of the present invention and need not be shown or described in detail.
- While I have shown and described certain embodiments of my invention I wish it to be 25 understood that I do not desire to be limited to the details thereof as various modifications may occur to a person skilled in the art.
- Having now fully described my invention, what I claim as new and desire to secure by 30 Letters Patent, is:
1. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with 35 their forward ends projecting beyond the same, a movable device mounted near the forward end of said supporting frame to engage the projecting ends of said set of forms and hold the same against rearward movement when said carriage is moved rearwardly, and means controlled by said carriage to move said holding device to an inoperative position when said carriage is near its rearmost position and thereby release said set of 40 forms and permit the same to be moved beyond said holding means when said carriage is moved forwardly.
  2. In an autographic register, a supporting frame, a carriage movable lengthwise of said frame and having means to support a plurality of superimposed webs of paper provided with forms arranged in sets, said carriage having a part forming a writing table and so arranged that said webs may be led 45 about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, and an actuating device connected with said holding device to move the latter into and out of its operative position, said carriage and said actuating device having parts which cooperate to move said actuating device in one direction while said carriage is near its foremost position and to move said actuating device in the other direction while said carriage 50 is near its rearmost position.
  3. In an autographic register, a supporting frame, a carriage movable lengthwise of said frame and having means to support a plurality of superimposed webs of paper provided 55 with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, and means controlled by said carriage to move said holding device to an inoperative position when said carriage is near its rearmost position and thereby release said set of forms and permit the same to be moved beyond said holding means when said carriage is moved forwardly.
  4. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, and an actuating device connected with said holding device to move the latter into and out of its operative position, said carriage and said actuating device having parts which cooperate to move said actuating device in one direction while said carriage is near its foremost position and to move said actuating device in the other direction while said carriage 60 is near its rearmost position.
  5. In an autographic register, a supporting frame, a carriage movable lengthwise of said frame and having means to support a plurality of superimposed webs of paper provided 65 with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, and means controlled by said carriage to move said holding device to an inoperative position when said carriage is near its rearmost position and thereby release said set of forms and permit the same to be moved beyond said holding means when said carriage is moved forwardly.

with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, an actuating device extending lengthwise of said supporting frame, mounted for limited longitudinal movement with relation thereto and operatively connected with said holding device, and means for causing said actuating device to be moved in one direction by said carriage while the latter is near its rearmost position and for causing said actuating device to be moved in the other direction by said carriage while the latter is near its foremost position.

6. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, an actuating device connected with said holding device to move the latter into and out of its operative position, said carriage and said actuating device having parts which cooperate to move said actuating device in one direction while said carriage is near its foremost position and to move said actuating device in the other direction while said carriage is near its rearmost position, and means carried by said carriage and acting on said webs to cause the same to move forwardly with said carriage.

7. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, an actuating device connected with said holding

device to move the latter into and out of its operative position, said carriage and said actuating device having parts which cooperate to move said actuating device in one direction while said carriage is near its foremost position and to move said actuating device in the other direction while said carriage is near its rearmost position, and a holding device movably mounted on said carriage and comprising means to cause the same to operatively engage said webs when said carriage is near its rearmost position.

8. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, an actuating device extending lengthwise of said supporting frame, mounted for limited longitudinal movement with relation thereto and operatively connected with said holding device, stops secured to said actuating device, a part carried by said carriage to engage one of said stops and move said actuating device in one direction when said carriage is near its rearmost position and a second part carried by said carriage to engage the other of said stops and move said actuating device in the other direction when said carriage is near its foremost position.

9. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, an actuating device extending lengthwise of said supporting frame, mounted for limited longitudinal movement with relation thereto, and operatively connected with said holding device, a stop having means for securing the same to said actuating device in different positions lengthwise thereof, a part carried by said carriage to engage said stop and move said actuating device to the limit of

its movement to actuate said holding device and interrupt the movement of said carriage.

10. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, means controlled by said carriage to move said holding device out of engagement with said set of forms while said carriage is near its rearmost position and thereby permit said set of forms to be moved beyond said holding device by the next forward movement of said carriage, and to move said holding device into operative engagement with a second set of forms after the first mentioned set of forms has been moved beyond said holding device, and means for preventing the direction of movement of said carriage being reversed until it has completed its movement in the direction in which it has started.

11. In an autographic register, a supporting frame, a carriage movable lengthwise of said frame and having means to support a plurality of superimposed webs of paper provided with forms arranged in sets, said carriage having a part forming a writing table and so arranged that said webs may be led about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, means controlled by said carriage to move said holding device out of engagement with said set of forms while said carriage is near its rearmost position and thereby permit said set of forms to be moved beyond said holding device by the next forward movement of said carriage, and to move said holding device into operative engagement with a second set of forms after the first mentioned set of forms has been moved beyond said holding device, and means acting on said carriage to prevent it being moved forwardly until it has completed its rearward movement.

12. In an autographic register, a supporting frame, a carriage movable lengthwise of said frame and having means to support a plurality of superimposed webs of paper provided with forms arranged in sets, said carriage having a part forming a writing table and so arranged that said webs may be led

about the rear end thereof and one set of forms positioned on said writing table with their forward ends projecting beyond the same, a movable device mounted near the forward end of said supporting frame to engage the projecting ends of said set of forms and hold the same against rearward movement when said carriage is moved rearwardly, means controlled by said carriage to move said holding device out of engagement with said set of forms while said carriage is near its rearmost position and thereby permit said set of forms to be moved beyond said holding device by the next forward movement of said carriage, and to move said holding device into operative engagement with a second set of forms after the first mentioned set of forms has been moved beyond said holding device, and means for preventing the direction of movement of said carriage being reversed until it has completed its movement in the direction in which it has started.

13. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device near the front end of said supporting frame comprising a pivoted member and a pin carried by said pivoted member and arranged to enter said set of openings when said carriage is near its foremost position and to hold said webs against movement when said carriage is moved rearwardly, and an actuating device operatively connected with said pin supporting member, said carriage and said actuating device having parts cooperating to cause said pin to be moved into said openings while said carriage is near its foremost position and to cause said pin to be withdrawn from said openings while said carriage is near its rearmost position.

14. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device in the forward end of said supporting frame and comprising a pin arranged to enter said set of openings when said carriage is near its foremost position and to hold said webs against movement

while said carriage is moved rearwardly to position said writing table beneath portions of said webs in the rear of a second set of openings, a pin movably supported on said carriage and arranged to enter said second set of openings when said carriage is near its rearmost position and means controlled by the movement of said carriage to withdraw the first mentioned pin from the first mentioned openings when said carriage is near its rearmost position, whereby the forward movement of said carriage will advance said webs and move said second set of openings into line with the first mentioned pin.

15. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device near the forward end of said supporting frame and comprising a pin arranged to enter said set of openings when said carriage is near its foremost position and to hold said webs against movement while said carriage is moved rearwardly to position said writing table beneath portions of said webs in the rear of a second set of openings, a pin movably supported on said carriage and arranged to enter said second set of openings when said carriage is near its rearmost position, means controlled by the movement of said carriage to withdraw the first mentioned pin from the first mentioned openings when said carriage is near its rearmost position, whereby the forward movement of said carriage will advance said webs and move said second set of openings into line with the first mentioned pin, and means controlled by the movement of said carriage while it is near its foremost position to move the pin on the carriage out of said second set of openings and to move the first mentioned pin into said openings.

16. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device near the forward end of said supporting frame and comprising a pin arranged to enter said set of openings when said carriage is near its foremost position and to hold said webs against movement

while said carriage is moved rearwardly to position said writing table beneath portions of said webs in the rear of a second set of openings, a second pin movably mounted on said carriage beneath said webs, means to cause said second pin to enter said second set of openings when it is brought into line therewith, and means controlled by the movement of said second pin into said second set of openings to cause the first mentioned pin to be withdrawn from the first mentioned openings and to interrupt the rearward movement of said carriage.

17. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device near the forward end of said supporting frame and comprising a pin arranged to enter said set of openings when said carriage is near its foremost position and to hold said webs against movement while said carriage is moved rearwardly to position said writing table beneath portions of said webs in the rear of a second set of openings, an actuating bar mounted for limited movement lengthwise of said supporting frame, operatively connected with said holding device and having a series of teeth arranged lengthwise thereof, a pawl mounted on said carriage for movement into and out of a position to engage one of the teeth on said actuating bar, a pin movably mounted on said carriage and arranged to enter said second set of openings when brought into line therewith, an operative connection between the last mentioned pin and said pawl to cause the latter to be moved into operative engagement with a tooth of said actuating bar when said last mentioned pin enters said second set of openings, whereby the further rearward movement of said carriage will cause said pawl to impart operative movement to said actuating device.

18. In an autographic register, a supporting frame, a carriage mounted for movement lengthwise of said frame and having means for supporting a plurality of superimposed webs of paper having alined openings spaced apart equal distances lengthwise of said webs, said carriage having a part forming a writing table and so arranged that said webs may be led about the rear end thereof and positioned above said writing table with one set of alined openings adjacent the front end thereof, a holding device near the forward end of said supporting frame and comprising a pin arranged to enter said

second set of openings when said carriage is near its foremost position and to hold said webs against movement while said carriage is moved rearwardly to position said writing table beneath portions of said webs in the rear of a second set of openings, an actuating bar mounted for limited movement lengthwise of said supporting frame, operatively connected with said holding device and having a series of teeth arranged lengthwise thereof, a pawl mounted on said carriage for movement into and out of a position to engage one of the teeth on said actuating bar, a pin movably mounted on said carriage and arranged to enter said second set of openings when brought into line therewith, an operative connection between the last mentioned pin and said pawl to cause the latter to be moved into operative engagement with the tooth of said actuating bar when said last mentioned pin enters said second set of openings, and cause the first mentioned pin to be moved to an inoperative position, the pin on said carriage being so arranged that when said carriage is moved to its foremost position it will be positioned beneath the first mentioned pin, and means controlled by the movement of said carriage when near its foremost position to move the first mentioned pin downwardly to eject the last mentioned pin from said second set of openings and to cause the same to engage beneath said webs when said carriage is again moved rearwardly.

35 19. In an autographic register, an outer casing having an opening in the top wall thereof, an inner casing slidably mounted in said outer casing, and adapted to contain a plurality of superimposed webs of paper having alined openings spaced apart lengthwise thereof, said inner casing having a part forming a writing table arranged to be moved into line with the openings in said outer casing and having an opening near the rear end of said writing table through which said webs may be led and positioned on said writing table, a pin movably mounted near the forward end of said outer casing and arranged to enter one set of alined openings in said webs when said inner casing is near its foremost position and to hold said webs against movement when said inner casing is moved rearwardly, means controlled by the movement of said inner casing to move said pin out of said openings when said inner casing is in its rearmost position, and means carried by said inner casing to cause said webs to move with the same when said inner casing is moved forwardly.

60 20. In an autographic register, an outer casing having an opening in the top wall thereof, an inner casing slidably mounted in said outer casing, and adapted to contain a plurality of superimposed webs of paper having alined openings spaced apart length-

wise thereof, said inner casing having a part forming a writing table arranged to be moved into line with the openings in said outer casing and having an opening near the rear end of said writing table through which said webs may be led and positioned on said writing table, a pin movably mounted near the forward end of said outer casing and arranged to enter one set of alined openings in said webs when said inner casing is near its foremost position and to hold said webs against movement when said inner casing is moved rearwardly, an actuating member operatively connected with said pin and having a part forming a stop, a pin movably mounted within said inner casing, means to cause said pin to enter a second set of openings in said web when said casing is near its rearmost position, and a pawl carried by said inner casing and so connected with the last mentioned pin that it will be caused to engage said stop on said actuating member and move the first mentioned pin out of the first mentioned openings when the last mentioned pin enters said second set of openings.

In testimony whereof, I affix my signature hereto.

PHILIP A. JACKSON.
